Inventor,

James Dodge

UNITED STATES PATENT OFFICE.

JAMES DODGE, OF WATERFORD, NEW YORK.

GRINDING AND POLISHING KNIVES.

Specification forming part of Letters Patent No. 21,746, dated October 12, 1858; Reissued May 31, 1859, No. 733.

To all whom it may concern:

Be it known that I, JAMES DODGE, of Waterford, Saratoga county, State of New York, have invented a new and useful

5 Method for Grinding and Polishing Knives or other Articles of Cutlery and Tools; and I declare the following specification, with the drawings hereto attached as part of the same, to be a full and perfect description

10 thereof.

Figure 1 is a perspective view of the machine I use. Figs. 2 and 3 are diagrams illustrating the operation of the machine.

Upon a strong frame A, A, A, A, a grind- 15 stone B is mounted on a shaft or axis a, a, properly fitted with journals and boxes and band wheels or gearing to revolve it with requisite velocity. Upon the same frame another shaft b, b, is arranged, with suitable 20 journals and boxes, lying parallel with shaft a, a. To this shaft is attached a cylinder C, arranged to revolve in the same direction with the grindstone B, by means of the bandwheel D with its band E passing 25 around drum G on shaft a (or by any other suitable gearing) by which the relative movement of the stone to the cylinder can be adjusted. This cylinder is intended to hold and carry the knives, or other articles 30 to be ground by the stone.

Upon the margin of the cylinder a flange H projects having suitable openings e, e, through it, at the surface of the cylinder, for the insertion, in the case of knife blades, 35 and similar articles, of their stems, to be confined with set screws tapped through the flange so as to lie properly upon the face of the cylinder to receive the action of the grindstone.

40 In order to adjust the articles with more exactness and certainty, there is sunk into the face of the cylinder a matrix or impression of the article as prepared for the grinding. This will prevent the article from 45 sliding along the surface of the wheel when under the attrition of the grindstone.

The grinding being effected by the revolution of the article on a curve, the result will be, if it be held immovably on the face 50 of the cylinder that the ground surface will be a convex of the curve or arc of the cylinder subtended by the article to be ground. The convexity of the form can be diminished, and the surface can be ground flat by 55 giving the cross section of the matrix x, y, an increasing convex shape, as shown in Fig.

2 where by sinking its outer edges f, f, equal to the sine g, of the curve, from f to f, and allowing the article being ground to rock on its curve, as it passes under the stone 60 a flat surface is produced. If the convexity of the bottom of the matrix be increased, (see Fig. 3,) the surface may be ground concave, like a razor blade.

For certain purposes it becomes convenient not to change the cylinder with every change of article to be ground. In that case I have the matrices formed upon segments of metal fitted to the curve of the cylinder so as to be affixed or removed without disturbing the cylinder.

In order to allow of the employment of grindstones of moderate width, when articles longer than that width are to be ground, the shaft of the cylinder is extended as 75 shown at I so as to permit the cylinder, which must be as wide as the article to be ground is long to be moved over the surface of the stone, or vice versa, the stone may be arranged to be moved over the surface of the cylinder.

In order to allow the proper play of the article in hand to form the desired surface flat or concave, the stem of the blade can be fitted into movable sockets, kept in 85 place by the set screws f, f, so as to be held down in the matrix, and yet turn sufficiently for grinding purposes.

For the polishing process, an emery wheel, or wheel covered with suitable polishing material is to be substituted for the 90 grindstone.

I claim—

1. The method of grinding and polishing articles and forming their surfaces upon a 95 revolving grindstone or polishing wheel by attaching them to a drum or cylinder which is made to revolve in the same direction with the stone or wheel and with velocity adjustable thereto, substantially as above set forth, 100 in the within specification.

2. I further claim the method of attaching and supporting upon a curved surface the article to be ground, so as to permit it to rock thereon, thereby shaping the surface 105 when formed either flat, concave or convex, substantially as above set forth.

JAMES DODGE.
